SPOOL AND METHOD FOR ITS
MANUFACTUREThomas George Baxenden, Watford, and John
Robert Collyear, Bushey, EnglandApplication August 21, 1931. Serial No. 558,621
In Great Britain February 26, 1931

3 Claims. (Cl. 242—71)

This invention relates to the construction and methods for their manufacture of spools such, for example, as those which are used for photographic films in roll-film cameras and the like although the construction herein described is applicable to spools for other purposes and the invention has for its object to devise a spool including its method of manufacture which shall be easier to construct and cheaper to manufacture than the constructions hitherto in use but which shall, nevertheless, be of sufficient rigidity and mechanical strength for the purpose for which it is to be used.

The invention relates more particularly to that type of spool which consists of a hollow, tubular spindle or barrel, to the ends of which, or near the ends of which, are attached metal end discs which serve to guide and retain the material, such as photographic film, as it is wound on the spool, although the construction is also applicable to a similar type of construction in which the spindle is solid.

According to the invention a spool of the above type, that is, comprising a tubular central spindle and end discs attached thereto, has its end discs secured in position by flanging the ends of the tubular spindle, shearing out a portion of the end discs so as to form a number of curved slots or openings in each end disc, arranged in the form of a circle of a diameter approximately equal to or larger than the diameter of the barrel, the outer edges of said slots being turned over by the shearing operation in order to allow the end of the barrel to be slipped therethrough, and then forcing the turned-over edges of the openings or slots back to their original positions in the plane of the disc and thus gripping the barrel tightly. Obviously the end of the barrel need not be flared but can retain its original diameter in which case the end is suitably cut to fit into the slots. By this method the end discs are securely held in their correct position on the barrel without any additional security in the way of welding or the like.

In the above construction it should be noted that no metal is removed from the end discs in forming the openings or slots, the latter being formed by shearing the metal along one edge of a slot and simultaneously turning back the metal occupying the position of the slot so as to form the required opening or slot.

A further feature of the invention consists in providing a construction of key stop which is clamped in position with one of the end discs.

In a modification of the above arrangement

the slots are replaced by a central hole formed in each end disc, of a diameter slightly less than the external diameter of the barrel, the edge of this hole is then turned over to allow the end of the barrel to be passed therethrough and the turned-over edge is then forced back to its original position so that it grips the barrel and secures the end discs firmly in position.

In this construction also no metal, apart from the cutting of the central hole, is actually removed in securing an end disc, the edge of the central hole in the latter being turned back out of the way to allow the barrel to be inserted, and then returned to its original position.

This latter construction is particularly applicable to spools having solid spindles.

The methods of construction will be more clearly understood by reference to the accompanying drawing which shows the constructions of photographic film spools for use in roll-film cameras. Fig. 1 shows a sectional view of one end of a spool showing its component parts disassembled at one stage in its construction; Fig. 2 is a similar view to Fig. 1 showing the end as a finished spool; Fig. 3 is a sectional view thereof taken through the line 3—3 (Fig. 2) and Fig. 4 is an end view of the finished spool. Figs. 5 and 6 show respectively an elevation and a plan view of the key stop; Figs. 7 and 8 are sectional views showing the modification applied to a spool of smaller size; while Figs. 9 and 10 are sectional views of a slightly different construction of the modified form of spool.

In all these views the reference numerals 1 and 2 indicate the barrel of the spool and an end disc, respectively.

In the construction shown in Figs. 1, 2, 3, and 4, an end disc is provided with a number of curved slots or openings 3 which are formed by shearing the material of the end disc along the inner edge of the slot and turning over the material occupying the position of the slot as at 4 to form the openings 3. Although only three such slots are here shown it will be understood that there may be only two or any other number of slots as may be required. These openings 3 are arranged in the form of an interrupted annular slot, the diameter across the inner edges of the interrupted annular slot being slightly greater than the normal diameter of the barrel 1 which is of tubular form, the end of the barrel being flared as at 5 to allow the end of the barrel to be inserted in the slots or openings 3. It should be noted that in forming the slots or openings 3 no metal is actually cut

away from the end discs, the openings being simply formed by shearing one edge thereof and turning the metal back by the shearing operation to form the required openings 3.

5 If the end disc is that having the usual key slot cut therein, there is inserted, between the end of the barrel and the flange or end disc, a key stop of the form shown in detail in Figs. 5 and 6. This key stop comprises a metal blank 10 formed to have a flat portion 6 and a depressed portion 7 of the shape shown, this latter portion receiving the end of the winding key. The length of the flat portion, between its curved ends, is approximately equal to the diameter 15 of the flared portion 5 of the barrel 1 so that when the flat portion of the key stop is placed between the end disc and the end of the barrel the flat portion 6 of the key stop will be clamped in position when the spool is completed. The key stop is positioned by the turned in edges of the key slot 8 in the end disc which fit inside the vertical sides of the portion 7 as clearly shown in Figs. 2 and 3. With the end 20 of the barrel and the key stop in position the outer edges 4 of the slots 3 are forced back into their original positions in the plane of the end disc and thus grip the flared portion of the barrel tightly. The end of the spool then has the form shown in Figs. 2, 3 and 4, which show 25 one end of a completed spool. The other end disc is similarly secured in position, although of course the end disc would have merely a central bearing hole instead of a key slot and no key stop would be provided.

30 By this method of construction the end discs, and key stop where fitted, are securely held in their correct positions on the barrel without any additional security such as welding or the like and the construction possesses great rigidity 35 and mechanical strength.

35 In the modified form of construction shown in Figs. 7 and 8 the method of construction is shown applied to a spool of smaller size for which this construction is particularly suitable. In this case a central hole, of a diameter slightly less than the external diameter of the barrel, is formed in each end disc and the edge 9 of this hole is then turned over as shown to allow the end of the barrel to be passed therethrough and 40 the turned over edge 9 is then forced back into its original position in the plane of the disc so that it grips the barrel and secures the end disc firmly in position. In the smallest sizes of spool the ends of the barrel extend beyond the 45 outer faces of the end discs, as shown, to form stub spindles in the usual manner. When the size of the barrel permits, however, the ends of the latter may have inserts 10 pressed therein, as indicated in Figs. 9 and 10, these 50 inserts being provided with holes 11 which form

5 a bearing upon which the spool revolves or a key slot for the winding key, respectively. When these inserts are fitted to the spool the end disc is secured flush with the end of the barrel since stub spindles are no longer required. It should be noted that in this case the end disc is securely fastened in position on the barrel before the insert is pressed into position and the latter does not contribute in any way towards securing the end disc as in a known construction in which an end cap is forced into the end of the barrel to grip the latter between itself and a deep collar on the end flange.

10 What we claim as our invention and desire to secure by Letters Patent is:—

15 1. A method of attaching the end flanges to the barrel of a spool, of the type comprising a tubular central barrel and end discs secured thereon, which consists in forming in each end disc a plurality of arcuate slots, arranged in the 20 form of an interrupted annulus, by shearing the end disc along a line which ultimately forms the inner edge of a slot and simultaneously turning back the metal occupying the position of a slot without completely removing any material, inserting the end of the barrel in the curved slots so formed and then forcing back the turned back edges of the slots substantially into their original position in the plane of the disc so as to grip the 25 edge of the end of the tubular barrel between the undeformed part of the end disc and the edges of the slots which have been forced back into position.

30 2. A method of attaching the end flanges of a spool, according to claim 1, wherein the end of the barrel is flared before being inserted in the slots.

35 3. In a photographic film spool, a tubular barrel, an end disc secured thereon by shearing and turning back portions of the latter to form slots into which the end of the barrel is inserted and 40 secured by forcing back the turned over edges of the slots substantially into their original position in the plane of the disc so as to grip the edge of the end of the tubular barrel between the undeformed part of the end disc and the 45 edges of the slots which have been forced back into position, a key stop formed from a metal blank to have a flat portion and a depressed portion receiving the end of the winding key, the flat portion having its edge inserted between the end disc and the end of the barrel before the turned over edges of the slots in the end disc are forced back into position, so that the edge of 50 said flat portion is gripped with the end of the barrel between the undeformed portion of the 55 end disc and the edges of the slots which have been forced back into position.

THOMAS GEORGE BAXENDEN.
